US0D1019986S

(12) **United States Design Patent** (10) **Patent No.:** **US D1,019,986 S**
(45) **Date of Patent:** **** Mar. 26, 2024**

(54) **ROLLING DOOR**

(71) Applicant: **Dongguan Geshengmei Industrial Co., Ltd.**, Dongguan (CN)

(72) Inventor: **Taotao Lei**, Dongguan (CN)

(**) Term: **15 Years**

(21) Appl. No.: **29/816,309**

(22) Filed: **Nov. 20, 2021**

(51) LOC (14) Cl. **25-02**

(52) U.S. Cl.

USPC **D25/48.4**

(58) **Field of Classification Search**

Primary Examiner — Leanne Was-Englehart

(57) **CLAIM**

The ornamental design for a rolling door, as shown and described.

DESCRIPTION

FIG. 1 is a perspective view of a rolling door showing my new design;

FIG. 2 is another perspective view thereof;

FIG. 3 is a front elevation view of a rolling door showing my new design;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures depict portions of the rolling door that form no part of the claimed design.

1 Claim, 8 Drawing Sheets
